UNITED STATES PATENT OFFICE.

JOSEPH H. LALIBERTE, OF NASHUA, NEW HAMPSHIRE, ASSIGNOR TO NASHUA MANUFACTURING COMPANY, OF BOSTON, MASSACHUSETTS, A CORPORATION OF NEW HAMPSHIRE.

WIND-DOWN MECHANISM FOR SPINNING FRAMES.

Application filed November 13, 1925. Serial No. 68,898.

This invention relates to spinning frames and similar machines used in the filling of bobbins or other thread packages hereinafter, for convenience, referred to as "bobbins".

5 It is the usual practice to wind or fill bobbins in a ring spinning frame, this machine being equipped with a builder motion which determines the manner in which successive layers of thread or yarn shall be wound on a 10 bobbin.

The present invention is especially concerned with machines of this type equipped with mechanism for building filling wound bobbins. Usually these machines are equipped 15 with a full bobbin stop motion which operates automatically to stop the machine when the filling of the bobbins has been completed. According to the common practice, the machine tender starts up the frame again immediately after it has been stopped and begins at once to wind down the ring rail by hand, stopping the frame again when the rail has been completely lowered. This results in 20 winding the yarn or thread in a spiral around the bobbin and then winding a few turns of 25 thread or yarn on the base of the bobbin.

With a view to reducing the care and labor involved in performing this operation, and producing more uniform results, it has been 30 proposed heretofore to perform the wind down operation automatically, and it is the general object of this invention to devise a superior mechanism for accomplishing this result.

35 In my copending application Serial No. 751,798, filed November 24, 1924, I have shown and described an automatic wind down mechanism which has proved very satisfactory in practice. The present invention, however, 40 aims to improve this mechanism still further with a view especially to simplifying the construction and reducing the expense of manufacture.

45 The nature of the invention will be readily understood from the following description when read in connection with the accompanying drawings, and the novel features will be particularly pointed out in the appended claims.

50 In the accompanying drawings,

Figure 1 is a side elevation of a portion of a spinning frame showing only those parts of the machine with which the invention is more especially concerned;

Figs. 2 and 3 are side elevations of certain 55 parts of the mechanism shown in Fig. 1, but illustrating successive steps in the operation of winding down the ring rail and stopping the machine;

Fig. 4 is a side view, partly in cross-section, 60 of the belt shifter and adjacent parts;

Fig. 5 is a transverse cross sectional view through a part of the spinning frame illustrating a portion of the mechanism which effects the winding down operation, certain 65 of the parts being shown in elevation;

Fig. 6 is a side view, partly in cross section, of the clutch and adjacent parts;

Fig. 7 is a plan view, partly in cross section, of the mechanism shown in Fig. 6; and 70

Fig. 8 is a front elevation of one of the clutch members and the lever which moves it.

In the machine shown, the ring rail is indicated at 2, this rail being supported by a series of vertical rods, one of which is shown 75 in Fig. 1 at 3. The lower end of this rod carries a foot which rests on a roll 4 supported at the outer end of an arm 5 which is secured rigidly to a cross shaft 6. A weight 7 also fastened to the cross shaft tends 80 to operate through the connections just described to lift the ring rail 2. The upward movement of the ring rail, however, is controlled by a builder motion indicated in general at 8, Fig. 1, and shown more completely 85 in Fig. 5. The lever 9 of the builder motion is connected by a chain 10 to a sector or arm secured fast on the rock shaft 6; a portion of this chain being wound on a drum 12, Fig. 5, which is slowly rotated a step at a time as the 90 lever 9 is reciprocated by the cam 13 during the operation of the machine, so that as the lever 9 swings up and down and thereby produces an alternate raising and lowering movement of the ring rail, the unwinding of the 95 chain 10 from the drum 12 will allow the rail to rise slightly between successive reciprocations. This results in building up the bobbin by the usual filling wind process. All of the mechanism so far described is constructed, 100 arranged and operated in the usual manner.

The machine is equipped with mechanism for automatically stopping it, this mechanism comprising a belt shifter 15, Fig. 4, secured on the end of a rod 16 and arranged to shift 105 the driving belt 17 from the fast pulley to the loose pulley 19, or vice versa. The rod 16 is mounted in the frame to slide longitudi-

nally. Adjustably secured on the end of this rod opposite to the shifter 15 is a small bracket or arm 20 which is in line with another rod 21 also mounted to slide longitudinally in the machine. A strong spring 22, Figs. 1, 2 and 3, is connected with this rod and tends to move it toward the right, thus operating through the arm 20, rod 16, and shifter 15 to move the belt 17 from the fast pulley 18 on to the loose pulley 19 to stop the machine. Normally, however, any movement of the rod 21 under the influence of the spring 22 is prevented by a pivoted latch 24 which engages a stop 25 that is adjustably secured on the rod 21.

The mechanism just described is under the control of a part movable in conjunction with the ring rail. That is, a rod 27 is supported at its lower end by an arm 28, Fig. 1, which is secured to the cross shaft 6, so that as this shaft is rocked by the builder motion during the progress of the bobbin winding operation, the rod 27 will gradually be raised until, when the building of the bobbins has been completed, the upper end of said rod will strike the latch 24 and lift it. This releases the stop 25 and allows the spring 22 to operate through the connections with the belt shifter to shut down the machine. The rod 27 is adjustably secured to the arm 28 so that it may be made to trip the latch 24 at any desired point in the rise of the ring rail 2.

The machine also includes a mechanism which is brought into operation automatically upon the tripping of the latch 24 to wind down the ring rail. This mechanism comprises a clutch including a driving member 30 and a driven member 31, the part 31 being mounted loosely on a driven shaft 32, while the part 30 is splined on said shaft. This shaft carries a sprocket wheel 33 which is connected by a chain 34, Fig. 5, to a part of the driving mechanism of the machine. Consequently, the shaft 32 is rotated continuously while the machine is in operation.

As shown, the clutch member 31 is integral with a disk 35 and a pin 36 projects from the face of this disk and is connected by a chain 37, Figs. 1 and 5, to an arm 38, Fig. 1, which is secured to the cross shaft 6. Normally the disk 35 is idle, and it is held by gravity in substantially the position shown in Fig. 6 due to the fact that the greater part of the metal of the disk is on the lower side of its axis as shown in said figure.

The clutch member 30 is grooved circumferentially to receive pins or rolls 39-39, Fig. 8, projecting toward each other from a lever 40 which straddles the clutch member 30 and is provided with a forwardly extending arm which normally bears against a collar 41 adjustably secured on the rod 21.

The weight of the lever 40 is so disposed that it tends to swing forward, or toward the right, Figs. 1 and 6, and thus to slide the

clutch member 30 into engagement with the clutch member 31, but this movement normally is prevented by the collar 41 and the fact that the latch 24 is holding the rod 21 against movement. When this collar 41 is withdrawn, the lever 40 then moves the clutch member 30 into engagement with the clutch part 31, thus bringing this part into operation, and the rotary motion of the part 31 is transmitted through the chain 37 and its connections with the ring rail to lower or wind down said rail.

When the machine is in operation the bobbin building process proceeds in the usual manner until the bobbins have been filled to the desired height. At this time the upper end of the rod 27 trips the latch 24, as above described, and as shown in Fig. 2. The spring 22 instantly acts to move the rod 21 to the right, but this movement is interrupted almost immediately by the engagement of the stop 25 with an arm 47 pivoted at 48, Fig. 1, and adjustably secured by a bolt 49 to the upper end of the rod 27, so that this arm moves in conjunction with the ring rail. Upon the release of the stop 25 by the latch 24 the rod 21 is allowed to move just far enough to permit the lever 40 to throw in the clutch 30-31 before the arm 47 catches the stop 25 and prevents further movement of the rod 21 toward the right. This movement is not sufficient to shift the belt 17, but it does serve to initiate the operation of the mechanism that winds down the ring rail, this function being performed by the clutch 30-31, disk 35, chain 37, and the connections between said chain and the ring rail.

As the ring rail moves downwardly, the arm 47 and rod 27 move in conjunction with it and as soon as the free end of the arm 47 slides down past the stop 25, the spring 22 operates through the rod 21 and the shifter 15 to move the belt on to the loose pulley 19, thus stopping the machine. It will be observed that while the action of the stopping mechanism is initiated by the rise of the ring rail to a predetermined elevation during its building movement, the completion of this operation is under the control of the arm 27 which also moves with, or in conjunction with, the ring rail 2. The point at which the arm 47 permits the belt shifting mechanism to function can be adjusted with reference to the movement of the ring rail by loosening the bolt 49 and moving the arm 47 up or down on the rod 27.

When the disk 35 has rotated far enough to complete the depression of the ring rail, the upper end of a latch 50 which is mounted on the outer end of the arm 5, Fig. 1, slips under the frame part 51 and locks the ring rail in its lowermost position. A coiled spring 52 holds the latch forward in its operative position. It may be swung backward against the action of the spring by stepping on the treadle.

or foot piece 53 which projects from the latch, the latch and treadle, in effect, forming a bell crank lever.

The parts are so proportioned that half a

- 5 revolution of the disk 35 effects the winding down of the ring rail. Just before the disk 35 has rotated through an angle sufficient to bring the ring rail into its lowermost position, a cam lug 55, Fig. 7, which projects from 10 the back of the disk 35, engages another cam lug 56 on the lever 40 and forces this lever backwardly far enough to disengage the clutch faces of the parts 30 and 31. This movement swings the upper end of the lever 15 40 toward the left, Figs. 1 and 3, far enough to permit the latch 57 to drop in behind the end of the lever, as clearly shown in Fig. 3, and thus lock the clutch in its disengaged or inoperative position.
- 20 The machine now is in condition for the doffing operation, and it has been brought into this condition automatically, no attention on the part of the operator having been required up to this point. After doffing, the 25 operator winds down the builder motion in the usual manner, and then throws the usual hand lever (not shown) which is connected with the rod 16 to move this rod toward the left, Fig. 1, far enough to shift the belt 17 back on to the fast pulley 18. At substantially the same time the operator releases the latch 50 thus starting the machine into operation again. As the rod 16 is moved toward the left the bracket 20 engages the end of the 30 rod 21 and moves it toward the left, thus restoring the parts to the positions in which they are shown in Fig. 1 with the latch 24 engaging the stop 25 and the collar 41 bearing against the upper end of the lever 40. As the 35 collar 41 moves toward the left it lifts the latch 57 out of engagement with the end of the lever 40.

This invention thus provides a mechanism for winding down the ring rail which is entirely automatic in its action, which is very simple in construction and can be manufactured very economically. The mechanism is of a very sturdy construction, is not liable to get out of order, and requires a minimum of care and attention on the part of the operator. It should be noted that in this machine the full bobbin stop motion simply initiates the operation of the stopping and wind down mechanisms, but the actual stopping of the machine is under the control of the arm 47 which moves in conjunction with the ring rail so that the machine is not permitted to stop until the ring rail has been wound down to a predetermined point. This arrangement has the advantage of controlling very accurately the amount of yarn which is wound on the bases of the bobbins.

While I have herein shown and described the best embodiment of my invention that I have so far devised, it will be evident that the

invention may be embodied in other forms without departing from the spirit or scope thereof. For example, the part 35 has been made in the form of a disk but this part might be in the form of a lever or arm. Other flexible connections, also, may be substituted for the chain 37, and various other changes may be made within the spirit or scope of the invention.

Having thus described my invention, what I desire to claim as new is:

1. In a ring spinning machine, a mechanism for automatically winding down the ring rail comprising a part normally idle but mounted for rotary motion about an axis, so a flexible connection between said part and the ring rail whereby the motion of said part may be utilized to lower said ring rail, means rotatable about said axis for driving said part, said means and part being arranged to be operatively connected with and disconnected from each other during the operation of the machine, mechanism arranged to operate automatically when the ring rail reaches a predetermined elevation 90 during its building movement to operatively connect said means and said part, and mechanism for disconnecting said means and said part again after the ring rail has been lowered.

2. In a ring spinning machine, a mechanism for automatically winding down the ring rail comprising a part normally idle but mounted for rotary motion about an axis, a flexible connection between said part and the ring rail whereby the motion of said part may be utilized to lower said ring rail, a driven member rotatable about said axis, said member and part having cooperating clutch faces to engage each other, and mechanism operative automatically when the ring rail reaches a predetermined elevation to cause said clutch faces to engage each other.

3. In a ring spinning machine, a mechanism for automatically winding down the ring rail comprising a part normally idle but mounted for rotary motion about an axis, a flexible connection between said part and the ring rail whereby the motion of said part may be utilized to lower said ring rail, a driven member rotatable about said axis, said member and part having cooperating clutch faces to engage each other, mechanism operative automatically when the ring rail reaches a predetermined elevation to cause said clutch faces to engage each other and thereby to wind down the ring rail, and means arranged to be operated by said part to disconnect it from said member after the ring rail has been lowered.

4. In a ring spinning machine, a mechanism for automatically winding down the ring rail comprising a shaft, a disk loosely mounted on said shaft, a flexible connection between said disk and said ring rail, a clutch

member mounted on said shaft, means for rotating said clutch member, said disk having a clutch face to engage the clutch face of said member, a lever for sliding said clutch member longitudinally of said shaft into and out of engagement with said disk, mechanism arranged to operate automatically through said lever when the ring rail reaches a predetermined elevation to cause said clutch member to engage said disk and thereby rotate the disk, and cooperating cam members on said disk and lever arranged to throw said clutch member out of engagement with said disk when the disk has rotated through substantially a predetermined angle.

5. In a ring spinning machine, a mechanism for automatically winding down the ring rail comprising a shaft, a disk loosely mounted on said shaft, a flexible connection 10 between said disk and said ring rail, a clutch

member mounted on said shaft, means for rotating said clutch member, said disk having a clutch face to engage the clutch face of said member, a lever for sliding said clutch member longitudinally of said shaft into and out of engagement with said disk, a spring actuated rod normally restraining said lever and holding the clutch member out of clutching relationship to said disk, a latch for restraining the movement of said rod, means 25 connected with the ring rail and arranged to be moved therewith for tripping said latch when the ring rail has reached a predetermined elevation, and cooperating cam members 30 on said disk and clutch member arranged to disengage said clutch faces automatically when the disk has been rotated through substantially a predetermined angle.
